United States Patent Office

Des. 223,663
Patented May 23, 1972

223,663

NIGHTSTICK

Frank E. Bortzfield, L-14 Lake Lotawana,
Lee's Summit, Mo. 64063

Filed Dec. 8, 1969, Ser. No. 20,406

Term of patent 14 years

Int. Cl. D22—02

U.S. Cl. D22—99

Fig. 1.

Fig. 2.

Fig. 3.

Fig. 4.

FIG. 1 is a front elevational view of a nightstick embodying my new design;

FIG. 2 is a side elevational view thereof;

FIG. 3 is an enlarged, top plan view thereof; and

FIG. 4 is an enlarged, bottom plan view thereof. The thong is shown in broken lines in FIGS. 1 through 4 for illustrative purposes only.

I claim:

The ornamental design for a nightstick, as shown and described.
